UNITED STATES PATENT OFFICE.

EARL E. EBY, OF WILKINSBURG, PENNSYLVANIA, ASSIGNOR TO WESTINGHOUSE ELECTRIC AND MANUFACTURING COMPANY, A CORPORATION OF PENNSYLVANIA.

BAROMETRIC VALVE.

1,266,566.

Specification of Letters Patent. Patented May 21, 1918.

Application filed July 6, 1915. Serial No. 38,118.

To all whom it may concern:

Be it known that I, EARL E. EBY, a citizen of the United States, and a resident of Wilkinsburg, in the county of Allegheny and State of Pennsylvania, have invented a new and useful Improvement in Barometric Valves, of which the following is a specification.

My invention relates to valves of the 10 barometric type, and it has for an object to provide means whereby a valve of the character indicated may be simply and effectively controlled and whereby it may be protected from mechanical injury.

15 Another object of my invention is to provide simple and inexpensive means for conveying current to an insulated electrode in a vapor converter or similar apparatus and, furthermore, to provide means whereby a 20 temperature-controlling fluid may be circulated through an electrode of the character indicated.

The single figure of the accompanying drawing is a side view, partially in section 25 and partially in elevation, of a vapor converter including a valve constructed in accordance with my invention, together with the necessary attendant auxiliary apparatus.

In the operation of vapor-electric apparatus, such, for example, as vapor converters of the large size metal case type, it is necessary to provide means whereby a pump may be readily connected and disconnected from the interior of the converter, the disconnecting means being of such character as to permit practically no leakage at the extremely high vacuum employed. One of the simplest and most obvious types of apparatus to employ for this purpose is the well 35 known barometric seal but the use of devices of this character has hitherto been limited by the fact that the seal was somewhat difficult to operate and was, furthermore, cumbersome and easily broken in commercial 40 use, having a minimum inherent length of at least twenty-nine inches when employing mercury as the sealing fluid.

I have provided an extremely simple and effective system of pneumatic control for a 50 barometric seal whereby it may be conveniently and expeditiously closed from a considerable distance, if necessary, and, by placing the seal itself entirely within the container of a vapor converter, its operation

is in no sense impaired but it is effectually 55 protected from mechanical injury.

By the expression "barometric seal," I refer to that class of structures wherein the difference of pressure between the atmosphere or a given inclosed space and the interior of a more or less highly evacuated container is balanced, in a tube connecting 60 said two spaces of different gas pressure, by means of a body of liquid, preferably mercury. By increasing or decreasing the 65 amount of said sealing fluid by pneumatically injecting or withdrawing the same, I am enabled to conveniently and accurately control the opening or closing of said tube to the passage of gas therethrough. I shall 70 hereinafter designate this combination of barometric seal, together with pneumatic operating means therefor, as a "barometric valve."

Furthermore, by constructing a barometric 75 valve of conducting material and causing it to extend into contact with an electrode within the container and by connecting a supply circuit to the exhaust tube, I am enabled to supply current to said electrode 80 through the same insulating joint that is employed for sealing the exhaust tube into the container wall, thus reducing the number of possible points of leakage in the container.

85 Referring to the accompanying drawing for a more detailed understanding of my invention, I have shown a vapor converter 1 comprising a container 2, preferably of the metal case type, an anode 3 and a cathode 90 pool 4, preferably insulated by means of a cup 5. An exhaust tube 6 projects through the cover of the container 2 and into contact with the material of the electrode 4 and is sealed into and insulated from said cover by 95 a suitable joint 7 of any desired form. The tube 6 is provided at its upper end with an outlet pipe 8 which is connected to a suitable exhaust pump 9, preferably through an insulating joint 10. A closed receptacle 11 100 surrounds the lower open end of the tube 6 and is partially filled with a sealing fluid 12, such, for example, as mercury. The receptacle 11 is composed of conducting material and its outer surface is in contact with the 105 material of the electrode 4. An internal exhaust tube 13 is sealed into the wall of the tube 6 at a point 14, at its upper end and is

in free communication with the interior of the container, and its lower open end terminates at a point above the lower end of the tube 6. A control tube 15 connects the space 5 within the receptacle 11 above the liquid 12 with a suitable control valve 16 through an insulating joint 17. The interior of the tube 15 may be connected either to the atmosphere or to a vacuum line by the manipulation 10 of a valve 16.

Having thus described the construction of my valve, the operation is as follows: Assuming the pump 9 to be running and the valve 16 to be in the position indicated. 15 The connection of the upper portion of the receptacle 11 with exhausting means disposes the mercury in the tube 6 as shown and air is drawn from the interior of the container 2 into the upper end of the tube 20 13, through said tube into the lower end of the tube 6 above the surface of the pool 12 therein and thence passes upwardly through the tube 6 to the pump 9. In order to close the main valve, the controlling valve 16 is 25 moved to connect the tube 15 with the atmosphere, whereupon the atmospheric pressure within the upper portion of the receptacle 11 forces down the mercury level of the pool 12 exterior to the tube 6 and 30 raises the level therein, first submerging the lower end of the tube 13 and then rising within the tubes 6 and 13 to a point indicated, for example, by a line 18, resulting in a sealing column having a length of from 35 twenty-nine to thirty inches if the container 2 is highly exhausted. The tube 15 is now closed by proper manipulation of the valve 16. If air leaks through the pump 9 into the tube 6, the mercury column therein will 40 drop, raising the level within the reservoir 11 to a greater or less degree. The fact that the upper portion of the receptacle 11 was charged to atmospheric pressure when the mercury column in the tube 6 stood at 45 the height 18 prevents the free flow of mercury thereinto and the back pressure which is developed permits the mercury within the tube 6 to fall only to some such point as is indicated by a line 19, at the same time 50 raising the level within the tube 13 to a point 20.

If desired, the entire barometric valve may be located exterior to the rectifier but for mechanical protection, I find it preferable to place it therein.

A conductor 21 may be clamped to the tube 8 so that current is supplied to the cathode 4 without the use of any joints in addition to that shown at 7 for the sealing 60 of the tube 6.

I may, if desired, place tubes for the circulation of cooling fluid for the cathode within the main tube 6 after the manner indicated in U. S. patent to Kraus & Mailey 65 #1,046,083, but supplementary features of

this character are obvious to those skilled in the art and constitute no part of the invention.

If it be found that the operating arc within the container 2 exhibits a tendency to 70 run up or injure the tube 6, an insulating shield 22 may be placed around the same, suitable openings 23 being placed therein below the level of the cathode 4 in order that the material of the latter may come 75 into intimate contact with the receptacle 11.

The use of a liquid sealing material, such, for example, as mercury, has been described throughout this case, but I may, if desired, substitute therefor a fusible material, such, 80 for example, as solder, applying heat when operating the same, all as described and claimed in a copending application of E. E. Rose, Serial No. 61,085, filed Nov. 12, 1915, and assigned to the Westinghouse Electric 85 & Manufacturing Company. When employing a solid sealing material, the valve is preferably located outside the container in order that it may be readily heated. The valve need not have the height of the cor- 90 responding barometric column as the rigidity of the sealing material, when cooled, prevents its displacement by atmospheric pressure.

While I have shown my invention in its 95 preferred forms, it will be obvious to those skilled in the art that it is susceptible of various minor changes and modifications without departing from the spirit thereof and I desire, therefore, that only such restrictions shall be placed thereupon as are imposed by the prior art or are specifically set forth in the appended claims.

I claim as my invention:

1. The combination with a closed container, of a pump external thereto, a tube connecting said pump with the interior of said container for transferring fluid therebetween, a valve for controlling the flow through said tube, said valve being located 105 entirely within said container, and pneumatic operating means for said valve located external to the container, the body of fluid operating medium for said valve being independent of the fluid body transferred between said pump and the interior of said container.

2. The combination with a closed container, of a pump external thereto, a tube connecting said pump with the interior of 120 said container, a barometric valve for controlling the flow through said tube, said valve being located entirely within said container, and pneumatic operating means for said valve located externally to the container, said pneumatic operating means being substantially independent of said pump.

3. The combination with a vapor converter including a closed container provided with an electrode at the bottom thereof, of 130

an exhaust tube projecting into said converter and into contact with said electrode, and connections from an external circuit to said exhaust tube, whereby said tube serves 5 as a current lead to said electrode.

4. The combination with a vapor converter including a closed container provided with an electrode at the bottom thereof, of an exhaust tube projecting thereinto and 10 provided with a valve entirely within said container, said valve extending into contact with said electrode and being provided with operating means, and connections from an electric circuit to said exhaust tube, whereby 15 said tube and valve operate to supply current to said electrode.

5. The combination with a vapor converter, of an exhaust tube connected thereto, and a valve of the barometric type for controlling said exhaust tube, said valve being mounted within said converter and being provided with operating means.

6. In a valve, the combination with a vertically disposed tube provided with a port 25 adjacent to its upper end and open at its lower end, of a second tube surrounding and incasing said first mentioned tube throughout the major portion of its length and extending below the lower end thereof, said 30 outer tube being provided with openings adjacent the upper and lower ends thereof, a body of sealing material surrounding the lower end of said outer tube and submerging the opening therein, and means for adjusting 35 the level of the surface of said body above and below the lower end of said inner tube.

7. In a valve, the combination with a vertically disposed tube provided with a port 40 adjacent to its upper end and open at its lower end, of a second tube surrounding and incasing said first mentioned tube throughout the major portion of its length and extending below the lower end thereof, said 45 outer tube being provided with openings adjacent the upper and lower ends thereof,

a pool of sealing fluid surrounding the lower end of said outer tube and submerging the opening therein, and means for varying the pressure on the surface of said pool exterior 50 to said outer tube for adjusting the surface thereof within said outer tube to points above and below the lower end of said inner tube.

8. In a valve, the combination with a vertically disposed tube provided with a port adjacent to its upper end and open at its lower end, of a second tube surrounding and incasing said first mentioned tube throughout the major portion of its length and extending below the lower end thereof, said outer tube being provided with openings adjacent the upper and lower ends thereof, a closed receptacle containing a body of sealing fluid surrounding the lower end of said 60 outer tube and submerging the opening therein, and means for varying the pressure within said receptacle, whereby the level of the said fluid within said outer tube may be adjusted to points above and below the 65 lower end of said inner tube.

9. The combination with a closed container, of a pump external thereto, a tube connecting said pump with the interior of said container, a valve for controlling the 75 flow through said tube, said valve being located entirely within said container and comprising an outer tube having an open lower end terminating in a pool of sealing liquid and an inner tube having an open 80 lower end terminating above the lower end of said outer tube, and pneumatic operating means for said valve located external to the container for varying the pressure on the surface of said pool exterior to said outer 85 tube in order to adjust the surface thereof within said outer tube to points above and below the lower end of said inner tube.

In testimony whereof I have hereunto subscribed my name this 28th day of June, 90 1915.

EARL E. EBY.
